THERMOSTATIC OVERLOAD SWITCHES

William G. Landwier, Fayetteville, N. Y., assignor to
Easy Washing Machine Corporation, Syracuse, N. Y.,
a corporation of Delaware

Application February 16, 1953, Serial No. 336,999

3 Claims. (Cl. 200—116)

This invention relates to thermostatic overload switches, and more particularly to those adapted for thermostatic and manual operation and use on domestic appliances.

The present invention is directed toward providing a rugged switch composed of few parts, free of pivots, certain of operation, readily assembled and low in cost of manufacture. The invention further is directed to providing a switch having a single manual operating member adapted to close or open the contacts, such switch having a thermostatic overload current-sensitive lock, so disposed in relation to the operating member as to be mechanically or thermally actuated to open the contacts.

The above and other novel features of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

In the drawings, wherein like reference characters indicate like parts:

Figure 1 is a side elevation of the internal mechanism, the casing being broken away;

Figure 2 is a horizontal section taken substantially on the line 2—2 of Figure 1;

Figure 3 is a transverse section taken on the line 3—3 of Figure 2;

Figure 4 is a diagrammatic perspective view of the moving parts with the push member 46 in exploded relation; and

Figures 5, 6 and 7 are diagrammatic figures showing stages in the operation of the switch.

In the drawings, there is shown a rectangular base plate 10 formed of insulating material secured to a box-like housing member 12, preferably of insulating material, such members being held together by fastening screws 14 and 16. The base plate is seated in an offset 18 extending around the inside periphery of the open end of the casing. Mounted on the base plate are a conductive terminal plate 20 centrally located, and at either end, a conductive terminal bracket 24 and a conductive contact supporting bracket 26. The terminal plate 20 is provided with a relatively stationary conductive contact 28 supported upon a U-shaped resilient conductive mounting member 30. The contact bracket 26 has an integral upstanding support post 32 to which is secured a resilient conductive leaf 34 having affixed thereto a contact 36 adapted to engage contact 28. The leaf 34 is stiffened along one edge by a flange 40, such flange terminating as at 42 short of the end of the leaf secured to the support post 32.

The leaf 34 is notched along one edge as at 44, and is adapted to be engaged by a manual push member 46 slidably mounted in the top 48 of the casing 12. The push member is formed of plastic or other suitable non-

2

conductive material, and may be substantially square in cross section, and is provided with a rounded end 50 within the casing, such end being adapted to engage the leaf 34 to move the contact 36 downwardly. Projecting beyond the rounded end 50 is an offset finger non-conductive extension 52 which extends through the notch 44 and is adapted to engage the upper horizontal end 54 of the U-member 30, supporting contact 28. The finger 52 is of sufficient length that upon depressing the push member 46, the finger engages the upper end 54 of the resilient contact member 30 after the end 50 engages the leaf 34, but before the leaf 34 is depressed sufficiently to close the contacts 36 and 28. Thus, the downward movement of the push member 46 does not close the contacts 28 and 36. A resilient leaf member 56 secured to the under side of the top wall 48 of the casing 12 extends across one side of the push member 46 and through an inclined notch 58 in the side wall of the push member 46. Such leaf spring is adapted to normally return the push member to the position shown in Figure 1.

The terminal bracket 24 is provided with an upstanding integral conductive post 60 while the post 32 is provided with a longitudinally extending conductive bracket portion 62. Extending between the post 60 and bracket 62 is a resilient conductive strap assembly composed of a bimetallic heat-sensitive member 64 and a conductive U-spring 66, the bimetallic member and U-spring being secured together as at 68. The end of the U-spring 66 is secured to the post 60 as at 70, while the bimetallic strap is supported at one end thereof upon the bracket 62. The bimetallic strap at its other end is notched as at 72 and the end portion 74 thereof deformed so as to lie in a plane forming an acute angle with the plane of the supported end of the bimetallic strap. The inclined portion 74 forms a cam and the lower edge 76 thereof is adapted to engage the tip end 78 of the leaf 34 to form a lock when such leaf is moved downwardly by operation of the non-conductive push member beyond the lower edge 76, it being understood that through such action, the bimetallic strap is cammed laterally away from the leaf as the tip end 78 is moved downwardly past the locking edge 76. It will be seen that when the leaf member bearing contact 36 is depressed by manipulation of the push member 46 to the locking position and thereafter the push member is released so as to return to the position shown in Figure 1, the finger 52 permits the return of the contact bearing portion 54 of the spring member 30, whereby the contacts 28 and 36 engage to close a circuit.

It will appear that the bimetallic member 64 is in a series circuit from the terminal bracket 24 to the supporting bracket 26 and through the contact leaf 34, contacts 36 and 28 and resilient member 30 to the terminal plate 20. It will also be understood that the bimetallic metal strap 64 is so constituted that upon a temperature rise, such strap will warp in a direction away from the leaf 34, that is, the surface of the bimetallic strap presented toward the leaf 34 will be rendered convex in varying degrees in accordance with the temperature generated therein. Thus, a current passing through the bimetallic strap 64 will effect a temperature rise therein, and if too great over a period of time, cause the bimetallic member and particularly the lock edge 76 at the extreme end thereof, to move away from locking tip 78 of the leaf member 34, so as to release the leaf 34 to open the contacts 36 and 28. In Figure 5, the switch parts are shown with the push member depressed. The finger 52 has engaged the upper end 54 of the contact member or leaf 30, preventing engagement of the contacts. The leaf 34 has been caused to pass the inclined portion 74 of the bimetallic leaf. In Figure 6, the push member has been allowed to return, whereupon the leaf

34 is held by the inclined portion 74, so that the contacts close. In Figure 7, the push member has been retracted so that the cam 80 (see Figure 4) has acted upon the inclined recess 82 to swing the bimetallic member away from the leaf 34, allowing leaf 34 to swing upwardly to open the contacts. Any heating of the bimetallic member due to overload has a similar effect, causing the inclined portion 74 thereof to swing so as to free the leaf 34, to open the contacts.

Manual means are provided for opening the contacts 28 and 36 through a movement of the push member 46 outwardly. The finger 52 is provided on its outer face with a camming surface 80, which is adapted to engage and ride against an inclined surface 82 formed in and along the lower edge of the bimetallic strap 64. Thus, upon moving the push member 46 outwardly from the position shown in Figure 1 a slight distance, the bimetallic strap is cammed outwardly away from the leaf 34 whereby the locking edge 76 is moving laterally out of engagement with the locking tip 78 at the end of the leaf 34.

The housing 12 is provided with a non-conductive projection 84 which may be molded integral therewith, which projection is adapted to engage the outer end of the leaf 34 to limit its upward movement, whereby such member may have a pre-stressed resiliency in the portion thereof adjacent the end fixed to the post 32. The terminal plate 20, brackets 24 and 26 may be secured in any suitable manner to the insulated plate 16, as by rivets 86. The other various members may be secured as by spot welds 88. The push member 46 is provided with a knob 90 having suitable recesses for receiving the end of the push member 46, such knob being held on the end by any suitable means such as a screw 92.

While a single embodiment of the invention has been illustrated and described, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. In an overload cutout switch, a non-conductive base, a conductive terminal block mounted thereon centrally thereof, a relatively stationary contact mounted on said block and facing away from said base, a conductive bracket at each end of said base, a resilient conductive contact leaf affixed at one end to one of said brackets, and projecting over said stationary contact, said leaf having a movable contact facing said stationary contact, and being biased to normally hold said contacts out of engagement with one another, a guideway mounted on said base and extending perpendicular to said base and in substantial alignment with the contact end of said leaf, a manual plunger slidably mounted in said guideway and adapted to engage said leaf upon downward movement thereof, a resilient conductive strap connecting said brackets and arranged laterally of and adjacent said leaf, and adapted for lateral movement with respect to said leaf, cam locking means on said leaf and strap adapted to hold said leaf in contact closed position, when moved to contact closed position by said plunger, a bimetal resistance section in said strap for moving said lock away from said leaf to open said contacts upon the heating of said section to a predetermined temperature, and non-conductive cam means on said plunger adapted upon upward movement thereof to engage said strap to move said lock away from said leaf to open said contacts.

2. In an overload cutout switch, a non-conductive base,

a conductive terminal block mounted thereon centrally thereof, a relatively stationary contact mounted on said block and facing away from said base, said contact being resiliently movable toward and away from said base, a bracket at each end of said base, a resilient conductive contact leaf affixed at one end to one of said brackets, and projecting over said stationary contact, said leaf having a movable contact facing said stationary contact, and being biased to normally hold said contacts out of engagement with one another, a housing for said contacts mounted on said base, said housing having a guideway extending perpendicular to said base and in substantial alignment with the contact end of said leaf, a manual plunger slidably mounted in said guideway and adapted to engage said leaf upon downward movement thereof, a resilient conductive strap connecting said brackets and arranged laterally of and adjacent said leaf, and adapted for lateral movement with respect to said leaf, cam locking means on said leaf and strap adapted to hold said leaf in contact closed position, when moved to contact closed position by said plunger, a bimetal resistance section in said strap for moving said lock away from said leaf to open said contacts upon the heating of said section to a predetermined temperature, and non-conductive cam means on said plunger adapted upon upward movement thereof to engage said strap to move said lock away from said leaf to open said contacts.

3. In an overload cutout switch, a non-conductive base, a conductive terminal block mounted thereon centrally thereof, a relatively stationary lower contact mounted on one end of a resilient U-strip having its other end secured to said block, said contact facing away from said base, said contact being resiliently movable toward and away from said base, a conductive bracket at each end of said base, a resilient conductive contact leaf affixed at one end to one of said brackets, and projecting over said stationary contact, said leaf having a movable contact facing said stationary contact, and being biased to normally hold said contacts out of engagement with one another, a housing for said contacts mounted on said base, said housing having a guideway extending perpendicular to said base and in substantial alignment with the contact end of said leaf, a manual plunger slidably mounted in said guideway and adapted to engage said leaf upon downward movement thereof, a non-conductive finger projecting beyond the end thereof for engaging said resilient U-strip to move said lower contact to prevent engagement with said leaf contact while said plunger is depressed, a resilient conductive strap connecting said brackets and arranged laterally of and adjacent said leaf, and adapted for lateral movement with respect to said leaf, cam locking means on said leaf and strap adapted to hold said leaf in contact closed position, when moved to contact closed position by said plunger, said resilient U-member moving said lower contact into contact engagement with said leaf contact when locked, and said plunger is released, a bimetal resistance section in said strap for moving said lock away from said leaf to open said contacts upon the heating of said section to a predetermined temperature, and non-conductive cam means on said plunger adapted upon upward movement thereof to engage said strap to move said lock away from said leaf to open said contacts.

4. In an overload cutout switch, a non-conductive base, a conductive terminal block mounted thereon centrally thereof, a relatively stationary lower contact mounted on one end of a resilient U-strip having its other end secured to said block, said contact facing away from said base, said contact being resiliently movable toward and away from said base, a conductive bracket at each end of said base, a resilient conductive contact leaf affixed at one end to one of said brackets, and projecting over said stationary contact, said leaf having a movable contact facing said stationary contact, and being biased to normally hold said contacts out of engagement with one another, a housing for said contacts mounted on said base, said housing having a guideway extending perpendicular to said base and in substantial alignment with the contact end of said leaf, a manual plunger slidably mounted in said guideway and adapted to engage said leaf upon downward movement thereof, a non-conductive finger projecting beyond the end thereof for engaging said resilient U-strip to move said lower contact to prevent engagement with said leaf contact while said plunger is depressed, a resilient conductive strap connecting said brackets and arranged laterally of and adjacent said leaf, and adapted for lateral movement with respect to said leaf, cam locking means on said leaf and strap adapted to hold said leaf in contact closed position, when moved to contact closed position by said plunger, said resilient U-member moving said lower contact into contact engagement with said leaf contact when locked, and said plunger is released, a bimetal resistance section in said strap for moving said lock away from said leaf to open said contacts upon the heating of said section to a predetermined temperature, and non-conductive cam means on said plunger adapted upon upward movement thereof to engage said strap to move said lock away from said leaf to open said contacts.
